UNITED STATES PATENT OFFICE.

EDWARD CLIFF, OF NEWARK, NEW JERSEY.

SPRING-SETTING MACHINE.

SPECIFICATION forming part of Letters Patent No. 457,073, dated August 4, 1891.

Application filed November 24, 1890. Serial No. 372,451. (No model.)

To all whom it may concern:

Be it known that I, EDWARD CLIFF, of Newark, in the county of Essex, in the State of New Jersey, have invented new and useful 5 Improvements in Spring-Setting Machines, of which the following, taken in connection with the accompanying drawings, is a full, clear, and exact description.

This invention relates to devices employed 10 for imparting the requisite bow or arch shape to the leaves of elliptic and semi-elliptic springs; and the invention consists in an improved organization of a machine which is capable of bowing or arching the spring-leaves 15 to the desired degree in a most effective and expeditious manner, and is adjustable to operate on spring-leaves of various dimensions.

The invention is fully illustrated in the annexed drawings, in which—

20 Figure 1 is a front elevation of a machine embodying my invention. Fig. 2 is an end view of the same. Fig. 3 is a vertical transverse section on line $x-x$, Fig. 1. Fig. 4 is a horizontal transverse section on line $y-y$, Fig. 25 1. Figs. 5 and 6 are respectively enlarged detached front and side views of the central bed-piece of the reciprocating spring-holding bed. Fig. 7 is an enlarged detached front view of another of the bed-pieces of the afore-30 said bed. Fig. 8 is a front view of the top portion of the machine, showing the same in its operative position. Fig. 9 is an enlarged top plan view of a portion of the flexible spring-bending head. Fig. 10 is a horizontal 35 transverse section of the spring-coupling of said bending-head. Fig. 11 is a perspective view of one of the bearing-blocks of said head. Figs. 12 and 13 are side and top plan views of the central bed-piece of the spring-40 holding bed, and Fig. 14 is a vertical section of the same seated in the said bed.

Similar letters of reference indicate corresponding parts.

A represents the main supporting-frame of 45 the machine, which is set in an erect position and rests with its base A' on a suitable foundation, and when the machine is arranged to be operated by gears, as shown, the said frame is formed with a wheel-pit A'', which is set 50 into the ground or foundation.

To the center of the top portion of the frame

A is secured a vertical guide G, in which is fitted to slide a hub B', formed integral with or rigidly attached to the center of the under side of the spring-holding bed B. This bed 55 receives a vertical reciprocating motion or up-and-down movement by means of eccentrics F F, fixed to a horizontal shaft I, which is journaled in suitable bearings on the base of the frame. Pitmen F' F' connect the eccen- 60 tries with the hub B', and rotary motion is imparted to the eccentrics by means of a gear-wheel I', with which engages a worm J, secured to a shaft J', which is journaled in boxes J'' J'' 65 on the frame A, and has driving-pulleys H H attached to its ends.

The spring-holding bed B consists of an elongated frame, in which are seated the bed-pieces e e e, the heads of which project above the top of the said frame. Said bed-pieces 70 are contiguous to each other and are clamped in the frame by set-screws f' f', inserted in opposite ends of the frame and bearing on the outer sides of the two end bed-pieces e e. All of the bed-pieces are adapted to be 75 moved vertically in the frame and to be set so as to cause the tops of said bed-pieces to come to a line more or less arching according to the degree of the arch or crown to be imparted to the spring to be operated on. By 80 means of a series of set-screws f'' f'', inserted in the side of the frame and bearing against the inclosed portions of the bed-pieces e e e, the latter are retained in their adjusted positions. To properly hold the spring s on the 85 reciprocating bed B, I clamp on opposite sides of the central bed-piece e two jaws f f, and in order to accommodate springs of various widths I make said jaws adjustable in relation to the width between them. For this 90 purpose I preferably provide the jaws f f with eyes, which are screw-threaded in opposite directions from each other, and pass transversely loosely through the central bed-piece e a right and left screw g, which works with its 95 opposite ends in the screw-threaded eyes of the jaws. By turning the screw g in one direction the jaws f f are caused to recede from each other to allow the spring s to be placed between them, and then by turning the afore-100 said screw in the opposite direction the jaws are caused to approach each other and grasp

between them the spring *s* so as to hold the same firmly in place. In order to insure the retention of the said spring central over the bed-pieces, I provide the central bed-piece 5 with shoulders *e'' e''* and rigidly secure to the screw *g* a collar *g'*, which is entered between the aforesaid shoulders, and is thereby confined laterally, and thus the screw *g* is prevented from moving longitudinally in the 10 bed-piece *e*.

Over or in front of the spring-holding bed B, and extending lengthwise thereof, is a flexible spring-bending head, which is normally straight and at right angles to the guide G. 15 Said spring-bending head consists, essentially, of a series of bearing-blocks *l l l*, distributed in front and lengthwise of the reciprocating spring-holding bed B, and flexible ties connecting said blocks together and to the frame A. Inasmuch as in the operation of the machine the said flexible spring-bending head is deflected in the shape of an arch by the pressure of the reciprocating bed B and spring *s* lying thereon, I form the bearing-blocks *l l* 20 with convex checks *l' l'* on their adjacent sides to allow said blocks to turn into the different angles which they have to assume in the aforesaid operation of the machine, as illustrated in Fig. 8 of the drawings.

For the flexible ties *D* and *D'* I prefer to employ suitable wire cables, each of which I bend at the center of its length so as to bring the two end portions parallel side by side. Each of the bearing-blocks *l* I provide with 35 two pairs of transverse perforations *l'' l''*, as shown in Fig. 11 of the drawings. Each of the cables passes through one of the pairs of perforations of the bearing-blocks *l l l*, and is tied at its extremities by a knob or head *m* on the 40 same.

To allow the normally-straight spring-bending head to be sprung into the shape of an arc by the pressure of the reciprocating spring-holding bed B, I connect the said head to the frame A by means of suitable spring-couplings, and also preferably provide said 45 couplings with hinges *c c*. To insure efficiency in the operation of the said spring-couplings, I form each of a box *C*, which has 50 trunnions *t t* on opposite sides and is open at its outer end. Said box is pivoted by its trunnions to the upper ends of arms *E E*, secured to the front and rear of the top portion of the frame A and extending upward 55 therefrom. In the box *C* slides a piston *C'*, and between said parts is interposed a stout spiral spring *a*, as shown in Fig. 10 of the drawings. Axially through the said piston and box passes the coupling-bolt *b*, the inner 60 end of which is connected to the cable *D* by a hinge *c*, and the outer end of said coupling-bolt is screw-threaded and provided with a nut *n*. By tightening said nut the tension of the spring *a* is adjusted to the requisite 65 degree to exert the necessary resistance to the draft of the cables *D D'* incident to the

deflection thereof when subjected to the pressure of the spring-holding bed B. The degree of the pressure of the bed B against the flexible spring-bending head is rendered 70 adjustable by regulating the normal distance between the said parts, and for this adjustment I dispose the arms *E E* with their upper ends inclined outward and connect said arms to the frame by bolts *u u*, passing through 75 the arms and through slots *v v* in the frame A, and parallel with the arms, as shown by dotted lines in Fig. 1 of the drawings. Said slots allow the arms *E E* to be raised or lowered to carry the flexible spring-bending head 80 a greater or less distance from the bed B.

Graduated scales *r r* are marked on the edges of the arms *E E* and adjacent portions of the frame A, by which scales the adjustment of the said arms can be determined. 85

For the purpose of cooling the blocks *l l l*, cables *D D'*, and underlying parts, I extend over the top of the machine parallel with the cables *D D'* a water-supply pipe *P*, which is provided with nozzles *P' P'*, as shown in Fig. 90 1 of the drawings, and the blocks *l l l* form with vertical grooves *o o* on their adjacent sides to allow the water to pass down to the underlying spring *s* and its supporting-bed B.

Having described my invention, what I 95 claim as new, and desire to secure by Letters Patent, is—

1. In combination with the frame and reciprocating spring-holding bed, a series of bearing-blocks distributed in front and 100 lengthwise of said bed, flexible ties connecting said blocks, and spring-couplings connecting said ties to the frame, as set forth.

2. In combination with the frame A and reciprocating spring-holding bed B, the boxes *C C*, pivoted to the frame at opposite ends of the said bed, pistons *C' C'*, sliding in said boxes, springs *a*, interposed between the pistons and their respective boxes, flexible ties *D D'*, connected to said pistons, and bearing-blocks *l l l*, connected to said ties, as and for the purpose set forth. 105

3. In combination with the frame A and reciprocating spring-holding bed B, the boxes *C C*, connected to the frame at opposite ends of 110 said bed, pistons *C' C'*, springs *a a*, hinges *c c*, connected to said pistons, flexible ties *D D'*, connected to said hinges, and bearing-blocks *l l l* on said ties, as set forth.

4. In combination with the frame A and reciprocating bed B, the arms *E E*, extending upwardly from the frame and connected to said frame, longitudinally-adjustable spring-couplings connected to said arms, a series of bearing-blocks distributed in front and 115 lengthwise of the bed B, and flexible ties connecting said bearing-blocks together and to said spring-couplings, as set forth. 120

5. In combination with the frame A and reciprocating bed B, the arms *E E*, extending 130 upwardly from the frame and connected thereto adjustably longitudinally, the boxes *C C*,

pivoted to said arms, pistons C' C' in said boxes, springs interposed between said pistons and boxes, flexible ties connected to said pistons, and bearing-blocks connected to said ties, as set forth.

6. In combination with the frame and reciprocating spring-holding bed, the flexible spring-bending head consisting of the separate wire cables D D', connected, respectively, to the frame at opposite ends of the aforesaid bed, a series of bearing-blocks l l l, strung on said cables, and heads on the ends of the cables bearing on opposite ends of the series of bearing-blocks, substantially as set forth.

15 7. In combination with the frame and reciprocating spring-holding bed, the flexible spring-bending head consisting of the series of bearing-blocks l l l, having convexed checks l' l' and perforations l'' l'', and the wire cables D D', connected to the frame respectively at opposite ends of the spring-holding bed and passing through the perforations of the said bearing-blocks and tied at their free ends to the ends of the series of blocks, substantially as described and shown.

25 8. In combination with spring-holding bed, the spring-bending head provided with slots extending vertically through said head, and

the water-supply pipe P, communicating with said slots, as set forth.

9. In combination with the spring-holding bed, the bearing-blocks flexibly connected together and formed with convexed checks l' l' and grooves o o, and the water-supply-pipe P, having nozzles P' P' communicating with the grooves o o, substantially as described and shown.

10. In combination with the frame A, reciprocating spring-holding bed B, and flexible spring-bending head D D' l, the boxes C C, 40 pistons C' C', springs a a, interposed between said boxes and pistons, the coupling-bolts b b, passing through the pistons and boxes and connected at their inner ends to the flexible spring-bending head and screw-threaded 45 at their outer ends, and adjusting-nuts n n on said outer ends of the coupling-bolts, as and for the purpose set forth.

In testimony whereof I have hereunto signed my name this 15th day of November, 50
1890.
